TOY RACING GAME

Frank Amico, Rochester, N. Y.

Application August 7, 1953, Serial No. 373,000

1 Claim. (Cl. 273—86)

The present invention relates to toys and more particularly to a toy which simulates the conditions of a horse race and which will permit several persons to play simultaneously a racing game simulating a horse race.

One object of the invention is to provide a game of the character described which is played with movable playing pieces simulating race horses and their jockeys, and in which the outcome of the game will be affected by the skill of the several players in manipulating their respective playing pieces, so as to arouse in the players thrills and excitement similar to those aroused at an actual horse race.

Another object of the invention is to provide a toy or game of the character described which will be simple in construction, strong, durable, and not likely to get out of order, and yet which will be easy to manipulate.

Other objects of the invention will be apparent hereinafter from the specification and from the recital of the appended claim.

In the drawing:

Fig. 1 is a side elevation and Fig. 2 is a plan view of a toy constructed according to one embodiment of this invention;

Fig. 3 is a fragmentary section on an enlarged scale taken on the line 3—3 of Fig. 2 and looking in the direction of the arrows and showing one of the game pieces and the means for manipulating the same in the at-rest position;

Fig. 4 is a similar fragmentary section but showing how the actuating cord for the game piece, when raised, imparts forward motion to the game piece;

Fig. 5 is a front elevation and Fig. 6 a side elevation on an enlarged scale of one of the game pieces;

Fig. 7 is a transverse section through the toy on an enlarged scale taken on the line 7—7 of Fig. 4 looking in the direction of the arrows;

Fig. 8 is a section on an enlarged scale on the line 8—8 of Fig. 1, looking in the direction of the arrows; and

Fig. 9 is a section on the line 9—9 of Fig. 8 looking in the direction of the arrows.

The game of the present invention comprises a base or support 20 (Fig. 7) which is in the form of a rectangular shaped box having a bottom 21, parallel sides 22, 22', parallel ends 23, 23', and a top 24.

The box may be made of heavy cardboard or light wood or of any other suitable material. In the embodiment shown, there are five parallel, elongate, preferably wood or plastic strips 30 mounted in the top of the box and spaced slightly from one another. These strips are glued or otherwise fastened at their ends to the partitions 45, 45', hereinafter referred to, and are supported intermediate their ends by blocks 32 that rest on the bottom 21 of the box. The narrow, elongate slots 31 between these strips 30 provide guideways in which the playing pieces travel in the playing of the game.

The playing pieces themselves, in the embodiment of the invention shown, are racing figures simulating a horse carrying a jockey and are denoted at 35. The simulated

2

fore feet of the horse are fixed in a button 36; and the simulated rear feet of the horse are fixed in a button 37. The buttons 36 and 37 are wider than the slots 31 between the strips 30 so that each button can rest on adjacent strips 30. In the embodiment of the invention illustrated, there are four slots 31 and four game pieces 35 to travel in these four slots, respectively.

Depending from each button 36 is a wire 38 that passes through the associated slot 31 and that is bent transversely at its lower end as denoted at 39 (Fig. 5) to provide a stop to prevent the playing piece from being thrown out of its guide slot 31 in playing the game. Depending from each button 37 is a wire 41 which is longer than the wire 38 and which is formed at its lower end with a loop 43. The playpieces 35 are adapted to be advanced by actuating strings 40. The several strings are designated, respectively, 40a, 40b, 40c, 40d (Fig. 8). Each string passes through the loop 43 of its associated playing piece. It is secured at one end in one end wall of the box and it is secured at its opposite end in a partition wall 45 or 45'. These partition walls are spaced from the end walls 23, 23', respectively, and are parallel thereto. The outside strings 40a, 40d are secured at their left hand ends in the wall 23, pass through apertures in the partition wall 45, and are secured at their right hand ends in the partition wall 45', while the inner strings 40b and 40c are secured at their left hand ends in the partition 45, pass through apertures in the partition wall 45', and are secured at their right hand ends in the end wall 23' of the box.

30 The four strings 40 are adapted to be actuated, respectively, by four separate actuating members 48 (Figs. 8 and 9), two of which are mounted between the partition 45 and the left hand end wall 23 of the box. The other two are mounted between the partition wall 45' and the right hand end wall 23' of the box. The actuating members 48 are wire members that are generally U-shaped, and that are mounted to pivot on pins 47 secured at one end in the end walls 23, 23' respectively, and at their opposite ends in the associated partition walls 45, 45', respectively, of the box. The legs 49 of each actuating member engage under one of the strings 40.

The actuating members 48 are adapted to be operated by push buttons 50. There are four of these push buttons disposed, respectively, in the four corners (Fig. 2) of the box to engage the bail portions 51 of the actuating members 48. Each push button is constantly urged to its uppermost position by a coil spring 54 (Fig. 9) which is interposed between a shoulder 55 on the push button and the bottom 21 of the box.

50 The strings 40 are normally loose. Each game piece ordinarily occupies the position shown in Fig. 3. When the push button associated with a particular game piece is depressed, the legs 49 of the associated actuating member 48 are rocked upwardly about the associated pivot pin 47, as shown in dotted lines in Fig. 9, lifting the associated string 40 and drawing it tight, as shown in Fig. 4. This lifts the rear end of the playing piece up, rocks it about its front button 36, and imparts to the playing piece a forward motion.

55 In playing a racing game, each player operates a separate push button 50. For convenience, as shown in Fig. 2, these push buttons may be individually numbered, 1, 2, 3, 4 to correspond to the numbers assigned to the different playing pieces whose starting positions may also be denoted by the numbers 1, 2, 3, 4, as shown in Fig. 2. Each player manipulates his own push button 50 to advance his own playing piece; and the one whose playing piece reaches the finish line first wins the race. Since the force and amount of the downward stroke of the pusher button 50 and the rapidity of its operation determines the rate of forward movement of the playing piece, it will be obvious that the game depends upon the skill of

the players. While the game is primarily a racing game, it will be obvious that an individual can amuse himself with the game by manipulating the pusher pin in various ways to simulate different gaits of a horse. For instance, by pushing a pusher button 50 downwardly repeatedly at a constant rate, the playing piece can be given simulated galloping motion.

While the invention has been described in connection with a simulated horse racing game, it will be understood that playing pieces may be used instead representing other animals or objects which it is desired to propel along a course.

While the invention has been described in connection with a particular embodiment thereof, then, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth and as fall within the scope of the invention or the limits of the appended claims.

Having thus described my invention, what I claim is:

A toy comprising a horizontal playing board having a plane top surface with a plurality of parallel, longitudinal slots therethrough, a plurality of playing pieces mounted on said board, each of said playing pieces being associated with one of said longitudinal slots and simulating a horse, each playing piece having front and rear leg portions which normally rest on the top surface of said board, each of said playing pieces having a member depending from its front leg portion which projects through its associated slot to prevent the piece from moving laterally with relation to said slot, means for lifting the rear leg portions only of said playing pieces off of the top surface of said board to impart a forward, sliding

movement to the front leg portions of said pieces resting on said board, said lifting means comprising a plurality of cord-like members, one for each playing piece, each cord-like member being fixedly secured at both its front and its rear end beneath said board in parallelism to one of said slots, a wire depending from the rear leg portion of each of said pieces through its associated slot and having a loop at its lower end through which one of said cord-like members passes, said cord-like members normally being loose, and manually operable means by which the cord-like members can be pulled taut to raise the rear leg portions of the playing pieces, so that when said cord is alternately pulled taut and then loosened the rear legs of said playing piece will move up and down giving said playing piece a galloping, forward motion over the top surface of said board, each of said cord pulling means comprising a vertically-reciprocable manually operable pusher, a pivotal lever mounted beneath said board for pivotal movement about a horizontal axis and in position to be engaged by said pusher when said pusher is actuated and in position to engage beneath one of said cord-like members, whereby when the associated pusher is depressed the associated cord-like member is lifted, there being a separate pusher and associated lever for each playing piece.
